W.B. Morton

UNITED STATES PATENT OFFICE.

PHILIP H. JUNG, OF MOUNT UNION, PENNSYLVANIA.

METHOD AND APPARATUS FOR SEPARATING COKE AND ASH.

Application filed November 8, 1919. Serial No. 336,689.

To all whom it may concern:

Be it known that I, PHILIP H. JUNG, a citizen of the United States, and a resident of Mount Union, Huntingdon County, Pennsylvania, have invented new and useful Improvements in Methods and Apparatus for Separating Coke and Ash, of which the following is a specification.

This invention relates to a method and apparatus for salvaging coke and imperfectly burned coal from ash and clinkers.

It is well known that the so-called ashes removed from furnaces and boilers contain a material percentage of coke and partially burned coal which has considerable fuel value. Heretofore it has been customary to obtain the coke and coal from the material removed from the furnace by mechanical separation, such as sifting and picking, which involves a labor cost ordinarily greater than the value of the coke and coal salvaged, and the separation of the coke and coal from the ashes has not, therefore, been generally practiced. It has been proposed to effect the separation by delivering the material from the furnace into a solution or suspension whose specific gravity is held at a desired value between the specific gravities of the coke and ash, allowing the coke to rise to the surface of the fluid, from whence it is removed, and allowing the ash to collect at the bottom of the tank. Proposed methods of this type are all open to serious objection. To obtain a solution of sufficient specific gravity to effect a separation an excessive amount of solid must be added, and trouble is invariably encountered due to crystallization. When a suspension is employed the suspended material invariably settles out along with the ash in the settling tank, and the specific gravity is reduced below that of the unburned coke or coal. By my invention I provide an economical and efficient method and apparatus for separating the coke and partially burned coal from the ashes and clinkers which is substantially automatic in its operation, requiring little labor and comparatively inexpensive apparatus and materials, and which is not open to the above stated objections.

I also provide means for reclaiming the materials used in separation of the coke and ash.

In carrying out my invention I take advantage of the difference in the specific gravities of the coke and partially burned coal

and the ash whereby when the mixture is delivered to a suitable tank containing material of the proper specific gravity the coke and ash may be directed in different paths and separately collected and discharged from the tank. In carrying out my invention I preferably use the apparatus embodying the principles disclosed in the accompanying drawings, wherein—

Figure 1 is a vertical sectional view of such apparatus; and

Fig. 2 is a plan view of the tank employed with parts shown in section.

Referring to the drawings, 1 indicates the main compartment of the tank which is preferably long and narrow and contains a solution or mixture of specific gravity about equal to the average specimen of coke or partially burned coal in the mass to be separated. This solution may be a concentrated brine or a sodium bicarbonate solution, or may be water having in suspension a sufficient quantity of sand or other finely ground siliceous or non-argillaceous material. Or, if desired, the sand or other insoluble material may be suspended in the salt or soda solution. This latter arrangement is particularly successful in that a separating medium of proper specific gravity may be obtained without encountering difficulty by reason of employing a solution of high concentration or excessive amount of material in suspension which is necessary where a pure solution or a pure suspension is used.

Supported above the tank is a hopper 2 in which the mixture to be separated is deposited either directly by suitable conveyors from the furnace, or otherwise, the hopper being provided with a feed 3 through which the material discharges in a thin layer onto a conveyor belt 4 leading to the surface of the fluid in the main tank.

At each side of the main tank separate compartments 5 are provided, each of which contains a paddle wheel 6 continuously driven, when the process is in operation, by a belt or otherwise, from the main power shaft 7. Port openings 8 leading into the main tank are provided at each end of the auxiliary tanks whereby the paddle wheels will produce a continuous and rapid circulation of the fluid through the main tank away from the feed belt 4, thence through the auxiliary tanks back to the openings adjacent the feed tank, so that the material

- delivered by the conveyor belt will be carried by the current in the main tank away from the feed conveyor toward the opposite end of the apparatus. As the ash and 5 clinkers are heavier than the coke, they will sink more rapidly in the fluid and a separation will be effected between the coke and the ash, the coke remaining on or near the surface where it will be carried by the flow 10 against a lifting conveyor 9 having suitable pockets or steps which engage the particles of coke and lift them out of the tank where they are discharged on a draining screen 10.
- 15 The ash and clinkers sink in the fluid with sufficient rapidity to reach a submerged conveyor belt 11 having its upper reach rotating in a reverse direction to the current, whereby the ash will be carried toward the 20 opposite end of the main tank. The submerged conveyor 11 discharges onto a second lifting conveyor 12 which lifts the ash out of the tank and discharges it onto a draining screen 13 on the opposite end of the 25 main tank under a wash water spray 14 and over a settling tank 19.
- Above the drain board 10 I also provide a wash water spray 14, the wash water draining through the screen onto a drain 30 board 15 into a small additional tank 16 between the main tank 1 and a settling tank 18 at the end of the apparatus.
- 35 The tank 16 is connected with the main tank 1 by a port opening 17 extending across the partition which separates the main tank from the tank 16, the port opening being preferably somewhat below the surface of the main tank so that the solution in the small tank will not be unduly agitated by the circulation of the solution in the main tank and the side compartments 5. Beyond 40 the tank 16 and beneath the drain board 15 there is provided an overflow compartment which is separated from the tank 16 by a partition of less height than the side walls 45 of the tank, whereby the liquid level in the tank 16, the main tank 1 and the side compartments 5 will be maintained at the height of the partition.
- 50 In connection with the above described apparatus I preferably employ an automatic feed hopper for maintaining the solution in the tank at the desired strength, although of course this is not necessary to successful 55 operation of the apparatus, as the solution may obviously be kept to strength by adding the salt or other matter to it from time to time, as required. The automatic feed may be of any desired design in which the opening of the feed valve is controlled by the strength of the solution. A small hopper 20 having a rotary valve 21 controlled by a float 23 on the end of the valve arm 22 arranged to extend into the solution, will answer the purpose quite well, the valve being

arranged to open when the float sinks in the solution, due to the lowering of the specific gravity of the solution by the addition of the wash water to the screens from the tank 16 through the port opening in the end partition of the main tank. 70

When the coke is discharged on the washing screen 10 the water from the spray 14 will wash the solution off the coke, carrying it through the screen onto the drain board 75 15, whence it is discharged into the auxiliary tank 16, this tank, the main tank and the side compartments being full of the solution when the machine is started with the end tanks 18 and 19 empty. As the operation 80 proceeds, the original solution is gradually taken out of the main tank on the surface of the coke and ashes from which it is washed by the sprays at either end of the apparatus, the portion of the salt or other 85 substance in the solution being returned to the main tank through the small tank 16, the purpose of which is to keep up the liquid supply in the main tank which would otherwise be gradually exhausted. As, however, 90 concentrated solution is taken out of the tank and replaced by solution more or less diluted with the wash water, the specific gravity of the solution becomes gradually 95 less and unless the salt or other substance was replenished from time to time by the automatic feed or otherwise, the separation would soon become ineffective. 95

By the arrangement described, the plant may be continued in operation so long as 100 material is added to the solution to keep up its strength. The apparatus as shown and described will preferably be operated until the settling tanks 18 and 19 at the ends of the apparatus are filled up. The apparatus 105 will then be stopped, the solution in the end tanks allowed to settle and water drained off if the solution merely contains the added substance in suspension or, if the solution is not of a character for the added substance 110 to settle out of it, the washings in the end tanks may be piped to an evaporator or other apparatus for recovering the salt or other substance. 110

By maintaining the solution in circulation in the manner described several useful 115 purposes are served. In the first place, the material to be separated is carried away from the feed belt and kept "thinned out" so that the particles can act independently 120 of each other in floating or settling. In the second place, by having the solution in circulation it is not necessary that it be sufficiently strong to actually float the coke while letting the ashes sink, as a mere difference in the rapidity of sinking properly timed with the rate of flow of the circulating fluid is all that is necessary to effect the separation, as the coke will be carried to its delivery belt before it sinks further than 125 130

the depth of the elevating pockets, while just a little greater rapidity in sinking on the part of the clinkers and ashes will cause them to reach the submerged belt. The circulation of the fluid also maintains the solution sufficiently agitated to keep the material in solution and its density uniform.

The apparatus may obviously be entirely automatic in its operation, and requires no labor other than keeping the hoppers charged and draining off the water from the settling tanks from time to time, so that the process may be profitably employed wherever there is an appreciable quantity of unburned coal or coke in the ashes discharged from the furnace.

It will of course be understood that the drawing is not intended to disclose the mechanical details of the feed hoppers, conveyors, etc., employed, as such devices are individually well known in the art.

It will also be understood that the process may be carried on without following the steps of washing the coke and ashes and recovering the material from solution, and that various modifications may be made in the apparatus without departing from the spirit of the invention as defined in the appended claims.

In the appended claims I have referred to the material to be salvaged as coke and the waste material as ash. It is to be understood that these terms are not to be used to indicate strictly the composition of the material, but broadly in the one instance to indicate the partially burned and unburned materials having a fuel value, and in the other instance to indicate the waste, whether ash, clinkers, slate, etc.

I claim:

1. The method of separating ash from coke which consists in feeding the material to be treated into one end of a vessel containing a fluid medium consisting of a combined solution and suspension of a specific gravity approximately equal to that of the coke while maintaining the fluid in said vessel continuously flowing toward the other end of the vessel, removing the coke and ash from said fluid at different levels, treating the separated material with wash water to remove the fluid medium, returning the wash water to the vessel, thereby causing said vessel to overflow, and collecting the overflow from the vessel for the recovery of the non-aqueous components of the fluid.

2. In an apparatus for separating ash from coke, the combination of a main tank adapted to contain a fluid medium consisting of a combined solution and suspension of specific gravity approximately equal to that of the coke, an auxiliary tank connected to the main tank, means for delivering material to be separated to the main tank near one end thereof, means for maintaining the fluid medium in the main tank in continuous circulation from the point of delivery toward the other end thereof, means for separately collecting and discharging the ash and coke from different levels, screening means on which the separated material is delivered, means for spraying the material on the screening means with wash water, and conducting the washings to the said auxiliary tank to replenish the liquid taken out of the main tank, and means actuated proportionally to the specific gravity of said fluid medium for admitting material to said tank and maintaining the specific gravity of said fluid medium at a substantially constant value.

3. In an apparatus for separating ash from coke the combination of a main tank adapted to contain a liquid of a specific gravity such that the ash will sink more rapidly than the coke, an auxiliary tank connected to the main tank, means for delivering material to be separated to the main tank near one end thereof, means for separately collecting and discharging the ash and coke, screening means on which the separated material is delivered, means for spraying the material on the screening means with wash water, return means positioned beneath said screening means for conducting the washings to the said auxiliary tank to replenish the liquid taken out of the main tank, and an overflow compartment adjacent said auxiliary tank to collect the surplus wash water for the recovery of the non-aqueous components of the fluid.

4. In a process of separating ash from coke, a separating medium comprising a combination of a true solution and a physical suspension, the resulting fluid being of specific gravity approximately equal to that of the coke.

Signed at Mt. Union in the county of Huntingdon and State of Pennsylvania, this 18th day of October, 1919.

PHILIP H. JUNG.
